(57) CLAIM

The ornamental design for a wallet, as shown and described.

DESCRIPTION

FIG. 1 is a front perspective view of a wallet according to an embodiment of the present invention.

FIG. 2 is a side elevation view of the wallet illustrated in FIG. 1.

FIG. 3 is another side elevation view of the wallet illustrated in FIG. 1.

FIG. 4 is a top plan view of the wallet illustrated in FIG. 1.

FIG. 5 is a bottom plan view of the wallet illustrated in FIG. 1.

FIG. 6 is a left side plan view of the wallet illustrated in FIG. 1.

FIG. 7 is a left side plan view of the wallet illustrated in FIG. 1.

FIG. 8 is a front perspective view of a wallet according to an embodiment of the present invention.

FIG. 9 is a side elevation view of the wallet illustrated in FIG. 8.

FIG. 10 is another side elevation view of the wallet illustrated in FIG. 8.

FIG. 11 is a top plan view of the wallet illustrated in FIG. 8.

FIG. 12 is a bottom plan view of the wallet illustrated in FIG. 8.

FIG. 13 is a left side plan view of the wallet illustrated in FIG. 8; and,

FIG. 14 is a right side plan view of the wallet illustrated in FIG. 8.

The broken lines depict elements of the wallet that do not form a claimed feature of the present invention.
